UNITED STATES PATENT OFFICE

JAMES M. McCLELLON, OF EVERETT, MASSACHUSETTS.

FIRE-BOX.

1,078,934.

Specification of Letters Patent. Patented Nov. 18, 1913.

Application filed December 16, 1912. Serial No. 736,897.

To all whom it may concern:

Be it known that I, JAMES M. McCLELLON, a citizen of the United States, and a resident of Everett, county of Middlesex, 5 and State of Massachusetts, (whose post-office address is 159 Beacham street, Everett, Massachusetts,) have invented an Improvement in Fire-Boxes, of which the following description, in connection with the accompanying drawings, is a specification, like characters on the drawings representing like parts.

This invention relates to fire boxes, and more particularly to fire boxes for locomotives.

In Letters Patent of the United States, No. 963,627 granted to me on July 5, 1910, there is shown and claimed a wall construction comprising a series of sections having 20 flattened adjacent sides, and curved or bulged sides facing the interior and exterior of the fire box. The form and construction of the sections is such that they are individually capable of flexion responsive to temperature changes and thereby prevent extension or distortion of the wall as a whole. It is a well known fact that pressure in a container tends to cause the wall thereof to assume a shape circular in 25 cross-section. The sections referred to were therefore made as nearly circular in section as possible in order to take advantage of the tendency of the steam to maintain a circular section, but in order to secure the 30 sections against extension in the direction of the length of the series and permit the sections to be nipped together, their sides were flattened throughout their lengths.

One of the principal objects of the present invention is to provide an arrangement for securing the sections in assembled relation which permits the use of sections which are circular or cylindrical substantially throughout their lengths.

45 The character of the invention may be best understood by reference to the following description of an illustrative embodiment thereof shown in the accompanying drawing, wherein:

50 Figure 1 is a vertical transverse section through an illustrative fire box embodying the invention; Fig. 2 on an enlarged scale is a sectional detail taken on line 2-2 of Fig. 1, showing the transverse form of the sections; Fig. 3 is a section taken on line 55 3-3 of Fig. 2; and Fig. 4 is a view similar

to that shown in Fig. 2 omitting an element shown in Fig. 2.

Referring to the drawing, the illustrative fire box there shown as embodying the invention comprises side walls 1, each including a series of upright sections 3. Each of these sections is cylindrical or circular transversely of the length of the series and substantially throughout the length of the 60 section. As a result, the pressure within the section tends to maintain the original shape of the same and the section is self-sustaining. This enables the use of a section of large diameter and having a thin shell 65 effective in generating steam and transversely expandible without danger of distortion thereof. Also the self-sustaining form of the sections eliminates the necessity of securing them together substantially 70 throughout their lengths. It is merely necessary to provide securing means adjacent the ends of the sections to maintain them in proper relation. This permits the use of sections which are smooth and uninterrupted by rivets or other securing means 75 substantially throughout their lengths and thereby free from projections which would invite the accumulation of sediment or scale.

It is desirable to provide some means of 80 communication between the sections in order that the water to be converted into steam may be supplied from one to the other. As shown herein, the lower ends of the sections are formed to present heads 85 conveniently integral with the cylindrical sections. These heads may be formed from the cylindrical stock of which the sections are made by annealing the lower ends of the sections and pressing the same to the 90 desired shape. The head may be of the same overall thickness in the direction of the length of the series as the diameter of the cylindrical portion of the section, but preferably is enlarged or bulged toward the 95 inner and outer sides of the wall. The head thus shaped presents flat sides or faces 100 of substantial extent providing an area of contact between the heads of adjacent sections sufficient readily to accommodate and 105 receive a nipple 9 entered through and expanded into registering apertures in the flat sides of such sections. The nipple being 110 expanded into registering apertures assists in holding the sides in proper relation. Preferably these nipples are placed near the lowest ends of the sections and permit a

free flow of water from one section to another. To close the lower ends of the heads of the sections, each is provided with a cup 11 or other suitable means shaped to conform to the contour of the interior of the head and riveted and welded or otherwise secured thereto.

To secure the sections against separation at their lower ends, a foundation ring or member 13 is provided common to the sections. To connect and secure the cups to this foundation ring the former are provided with medial tongues 15 depending therefrom and fitting a groove 17 extending longitudinally of the ring. To secure the tongues in the groove bolts 19 are entered through the ring and tongues. By this construction the lower ends of the sections are securely held without liability of displacement or separation from their proper positions.

A suitable crown is provided for the fire box, shown herein as side drums 21, 21 and two smaller intermediate drums 23, 25. The side wall sections are connected with the side drums. To effect this the upper end portion of the cylindrical stock of a section may be pressed to flatten a side thereof as at 27 to conform to the contour of the drum. In thus pressing this side the opposite side may bulge or offset slightly from the body of the section as at 29. To permit communication from the sections to the crown drums they are provided with registering apertures in which are expanded suitable nipples 31. The sections are riveted or otherwise secured to said drums around said nipples.

The upper ends of the sections may be closed by cups 33 riveted or otherwise secured to the sections. To facilitate the cleaning or flushing out of the sections these top cups may be provided with plugs 35 threaded therein and similar plugs 37 may be provided at the lower ends of the sections. The side walls may be secured to a flue sheet receiving flues 39 contained in a barrel 41. The crown drums may be entered into flanged apertures in this flue sheet and be riveted or otherwise secured thereto.

To permit the water to flow from the barrel into the walls of the fire box the sections adjacent the flue sheet may have nippled connections therewith (not shown). The water in the barrel will flow through the nipples into the side wall sections and rise therein to the nipples between the side wall sections and the drums. The water level is normally maintained at least as high as these nipples in order to prevent the uncovering of the lower surfaces of the crown drums which are exposed to the fire in the fire box.

In some cases, to connect the sections and

prevent the accumulation of dust or other foreign matter in the grooves formed at the junctures of the sections, fillers 43 (Fig. 2) may be introduced into said grooves. This may be conveniently done by gradually filling melted metal in the grooves so that it will be welded thereto and in effect form the wall sections into an integral whole. These fillers preferably are provided in the grooves between the sections facing the interior of the fire box, but if desired, similar fillers 45 may be introduced in the opposite grooves or those facing the exterior of the fire box.

The wall sections being large and of thin material, when subjected to the high heat within the fire box, are very efficient in developing and generating steam in the water in the sections. This creates pressure within the sections, but owing to their cylindrical or circular shape, this pressure will tend to maintain the cylindrical form of the sections and there will be no danger of distorting or weakening the same. The series of sections constituting the side wall of the fire box presents an extremely strong and effective construction, which is easy to manufacture and assemble. It is not necessary to rivet or otherwise secure the sections together at intervals throughout their lengths, but the sections are securely held together by their connection with the foundation ring common thereto at their lower ends and by their connection with the crown drum common thereto at their upper ends.

Having described one embodiment of the invention, without limiting the same thereto, what I claim as new and desire to secure by Letters Patent is:

1. In a fire box, the combination of a series of upright wall sections respectively circular, self-sustaining and individually expansible transversely of the series, means to secure said sections in assembled relation; and means permitting communication between said sections adjacent their lower ends.

2. In a fire box, the combination of a series of upright wall sections respectively of large diameter, circular, self-sustaining and individually expansible transversely of the series; and nipples connecting said sections adjacent their lower ends.

3. In a fire box, the combination of a series of upright wall sections respectively circular, self-sustaining and individually expansible transversely of the series and having flattened portions adjacent their lower ends; and means providing communication between said sections through said flattened portions.

4. In a fire box, the combination of a series of upright, wall sections respectively circular, self-sustaining and individually expansible transversely of the series and provided with heads adjacent their lower ends.

ends having flattened contacting surfaces; and means to secure said sections together.

5. In a fire box, the combination of a series of upright wall sections respectively circular, self-sustaining and individually expansible transversely of the series; means closing the lower ends of said sections; and a foundation member, said means and foundation member being formed for interlocking engagement.

6. In a fire box, the combination of a series of upright wall sections; cups closing the lower ends of said sections, a foundation member; and tongue and groove connections between said cups and member.

7. In a fire box, the combination of a series of upright wall sections; cups closing the lower ends of said sections, a foundation member, tongue and groove connections between said cups and member; and means to secure said tongues in said groove.

8. In a fire box, the combination of a series of upright sections cylindrical substantially throughout their lengths and having portions flattened and nipped together to provide communication between them, means closing the lower ends of said sections; and foundation means common to and secured to said closing means.

30 9. In a fire box, the combination of a crown, a series of upright wall sections respectively circular, self-sustaining and individually expansible transversely of the series, heads having flat faces at the lower ends of said sections, means to secure said lower ends in assembled relation; and means to secure the upper ends of said sections to said crown.

10. In a fire box, the combination of a 40 crown comprising a plurality of drums, side walls each comprising a series of upright cylindrical sections individually self-sustaining and expansible transversely of the series, means connecting upper portions of said sections to said drums, heads at the lower ends of said sections having flat engaging sides, nipples connecting said sides, means closing the lower ends of said sections and secured thereto; and foundation means 50 having tongue and groove connections with said closing means.

11. In a fire box, the combination of sides, each comprising a series of upright, hollow wall sections respectively cylindrical substantially throughout their lengths and having enlarged lower ends apertured and secured together, said sections being held together to form in effect an integral whole;

and crown drums secured to and communicating with said sides.

60

12. In a fire box, the combination of crown drums, side wall sections substantially cylindrical throughout their lengths and having upper ends flattened to conform to the contour of said drums and their lower ends formed with two flattened sides and with two bulged or convexed sides.

65

13. In a fire box, the combination of crown drums with upright sections cylindrical substantially throughout their lengths and having upper ends, each flattened on one side for connection with said crown drums, and lower ends, each flattened on two sides transversely to the flattened portions of the upper ends.

70

14. In a fire box, the combination of a series of wall sections respectively circular transversely of their lengths; and filler means welded to said sections and located in the grooves formed between the sections.

75

15. In a fire box, the combination of a series of wall sections respectively circular transversely of their lengths and welded together to form in effect an integral whole.

80

16. In a fire box, the combination of crown drums with a series of wall sections cylindrical substantially throughout their lengths and having their upper ends connected to and communicating with said drums and their lower ends enlarged, flattened and apertured to provide communication from one to another, the distance between the flattened portions of a section being substantially the same as the diameter of the cylindrical portion of the section.

85

17. In a fire-box, the combination of a series of hollow wall sections welded together to form in effect an integral whole.

90

18. In a fire-box, the combination of a series of hollow wall sections; and fillers interposed between and welded to said sections to form in effect an integral whole.

100

19. A fire-box comprising upright wall sections having their lower ends enlarged, apertured and united together.

105

20. A fire-box comprising a series of upright assembled wall sections having their lower ends enlarged and apertured to form water circulation means.

In testimony whereof, I have signed my name to this specification, in the presence of two subscribing witnesses.

JAMES M. McCLELLON.
